A. HUMMEL

OCULIST'S INSTRUMENT

Filed Sept. 23, 1925

Patented Jan. 10, 1928.

1,655,700

UNITED STATES PATENT OFFICE.

ANTON HUMMEL, OF ST. LOUIS, MISSOURI.

OCULIST'S INSTRUMENT.

Application filed September 23, 1925. Serial No. 58,114.

This invention relates generally to oculists' instruments and more particularly to a certain new and useful improvement in such instruments of the type commonly known as ophthalmoscopes, retinoscopes, and the like.

At the present time, so far as I am aware, the oculist, in the practice of his profession, usually has two separate such instruments, both of which are expensive and costly, one used by him at his office, where desired line-circuit current is conveniently obtainable, and one used by him when visiting a patient, where the desired line-circuit current is not conveniently or readily had. The primary object of my present invention is hence the provision of an efficient instrument of the type mentioned that may with ease and convenience and with accruing saving to the oculist be interchangeably employed by the oculist both at his office in connection with line-circuit service and on visits out of his office where line-circuit service is not obtainable.

And with the above and other objects in view, my present invention resides in the novel features of form, construction, arrangement, and combination of parts herein-after described and pointed out in the claims.

In the accompanying drawing,—

Figure 1 is an elevational view, partly broken away and in section, of an oculist's instrument of ophthalmoscope type interchangeably equipped according to my invention with a resistance coil for service connection with line-wire current;

Figure 2 is a transverse sectional view of the instrument, taken approximately on the line 2—2, Figure 1, looking in the direction of the arrows; and

Figure 3 is a fragmental elevational view, partly broken away and in section, of the instrument interchangeably equipped with a portable source of electric current.

Referring more in detail and by reference characters to the drawing, which in Figures 1 and 2 illustrates a preferred embodiment of my invention, 1 designates a preferably tubular shell or casing of suitable stiff insulation material, which is adapted to provide both the handle of the instrument and a container for certain of the electrical parts or elements thereof.

Adapted for interchangeable disposition lengthwise within shell 1, is a suitable elec-

tric battery or cell 2, as in Figure 3, and a suitable resistance coil 3, as in Figure 1.

Cell 2 is preferably of that type wherein its one end wall 2^a forms one terminal and 60 a button 2^b projecting from its other end forms the other terminal thereof.

Coil 3 preferably includes a suitably elongated insulation spool 4 provided at one end with a contact-button 5. Disposed lengthwise within spool 4, is a conducting preferably rectangular bar 6 provided within its length with one or more tapped openings, for purposes shortly appearing, and terminating at the end of the spool opposite the button 5 in alignment with a socket-opening 7 in an insulation piece 8 suitably fixed to the spool. Also fixed to the latter end of spool 4 about the insulation-piece 8, is a conducting-disk 9, having electrical connection 75 with which at one end is a short conducting-wire 10 fixed for electrical engagement at its other end in the wall of a second socket-opening 11 in the insulation-piece 8. Coiled on the spool 4, is suitable resistance wire 12, 80 interposed in which in alignment with said tapped openings of the bar 6, are one or more apertured plates 13 adapted selectively to receive a conducting screw 14 for engagement with the bar 6 to cut in more or less 85 of the resistance-wire 12, as may be desired or required.

Fixed upon one end of the body 1, is a conducting-ring 15 internally threaded for engagement with an externally threaded 90 flanged conducting-closure 16 suitably apertured centrally in its end wall to accommodate, when threaded upon the spool, the spool insulation socket-member 8, and adapted for disposition between the end-wall of the closure 16 and the end-disk 9 of the spool 4, as in Figure 1, or between the closure 16 and the end-wall 2^a of the cell 2, as in Figure 3, to provide electrical connection therebetween, is a conducting coiled spring 100 17 adapted also to yieldingly press the cell 2 or the spool 4 upwardly to maintain either the spool-button 5 or the cell-button 2^b, as the case may be, in electrical engagement with a contact-button, or, as recited in the 105 appended claims, a second contact-member, 18 projecting from an insulation closure 19 fixed upon a conducting annular member 20, in turn, fixed upon the other or upper end, and forming substantially a part, of the 110 body or shell 1.

Upstanding from the fixed closure 19, is

a suitable stem 21 diametrically reduced, as at 22, to receive and support the several lens and light carrying member 23 of the instrument. Inasmuch as the member 23 and its 5 associated and essential parts are of standard construction, well understood by those skilled in the art, I omit here detail description thereof. Suffice it now to say that disposed in stem 21, is a contact-pin 24, or, as 10 recited in the appended claims, a first contact member, with which the terminal 25 of the incandescent bulb 26 of member 23 is adapted to electrically engage when the member 23 is operatively seated upon the stem 21, as 15 shown. Further disposed in stem 21, are conducting-bars 27 one leading from the contact 24 to an arc-shaped conducting-strip 28 fixed upon the under-face of the closure 19 and the other leading to the conducting 20 ring 20, one end of the strip 28 being insulated, as at 29.

Electrically pivoted, as at 30, on the fixed button 18 and projecting outwardly of the shell 1 for movement in an annular closed- 25 end slot 31 provided in the fixed ring 20, is a switch-member 32 insulated, as shown, from the ring 20 and fixed at its outer end to, and also insulated from, an actuating 30 conducting ring 33 arranged for rotatory movement upon the fixed ring 20. Forming substantially part of switch-member 32, is a brush 34 adapted for movable electrical engagement with the strip 28, and normally, 35 as when the switch-ring 33 is in "off" position, resting upon the insulation portion 29 thereof. And electrically connecting the lower fixed ring 15 with the upper fixed ring 20 and disposed along the inner face of the shell 1, is a conducting-member or strip 35.

Now, normally, as I might say, as when the instrument is to be used or employed by the oculist as on a visit away from his office, a cell 2 is disposed within the shell 1, when the circuit to the bulb 26 will extend 45 through cell end-wall 2^a, wire coil 17, closure 16, ring 15, conducting strip 35, upper fixed ring 20, rotatory ring 33, one bar 27, bulb 26, and then from the bulb 26 through the other bar 27, strip 28, switch-member 32 and 50 contact-button 18 to the button 2^b of the cell. It will thus be evident that, as the ring 33 is rotatably moved, the switch-brush 34 will be shifted from said insulation 29 and on to the conducting portion proper of the strip 28 and the circuit to the bulb 26 from the 55 contained source of current 2 completed.

Now, on the other hand, if the instrument is to be used by the doctor in his office, it is preferred, in order that there may be a more 60 steady source of current than is usually provided by the cell 2, the closure 16 is detached to permit removal of the cell 2 and the interchangeable insertion within the shell 1 of the resistance coil 3, when the closure 16 is again 65 threaded into engagement with the ring 15.

Usually, however, the current of the line-circuit is too intense or of too high voltage to permit direct connection between the coil 3 and the line-circuit, and in order first to reduce the line-circuit to a proper or safe 70 voltage for the coil 3, I plug into the line circuit one terminal 36 of a suitable transformer 37 provided with a second pin-terminal 38, which is plugged into the insulation piece or socket-terminal 8, whereupon the 75 circuit through the instrument extends from the one terminal-pin 39 to the conducting strip 10, spool disk 9, the wire coil 17, enclosure 16, ring 15, conducting strip 35, ring 20, rotary ring 33 and one bar 27 to the bulb 26 and then from the bulb 26 through the other bar 27, strip 28, switch-member 32, and 80 contact-button 18 to the upper button 5 of the coil, and then through resistance wire 12 and the bar 6 to the other pin 40 of transformer terminal 38, electrical connection between resistance-wire 12 and bar 6 being 85 established by means of the insertion selectively of the conducting member 14 into one or the other of the apertured plates 13, and one or more units of the resistance being 90 thereby included in the circuit as may be desired to further reduce the intensity of the transformed current. The circuit is completed or closed and light bulb or other translating device 26 is then similarly energized 95 by actuation of the conducting ring 33.

Thus, I provide an instrument which the oculist may interchangeably employ both while at his office and while visiting patients 100 away from his office and thereby obviate the expense to the oculist of two separate instruments adapted one for use only at the office or in connection with a line-circuit where connection with the line circuit is obtainable, 105 and one usable when engagement with the line circuit is not obtainable.

I am aware that changes in the form, construction, arrangement, and combination of the several parts of my new instrument may 110 be made and substituted for those herein shown and described without departing from the nature and principle of my invention.

Having thus described my invention, what 115 I claim and desire to secure by Letters Patent is:

1. In an instrument of the class described, a shell open at an end, first and second contacts disposed in spaced relation on the shell, circuit-forming conductors between the first and second contacts, a switch mounted for movement on the shell and interposed in said conductors for closing and opening the circuit between said contacts, and means including a conducting closure for the open end of the shell having electrical connection with the first contact, in combination with a resistance-coil disposed within the shell intermediate the closure and the second contact 120
2. In an instrument of the class described, a shell open at an end, first and second contacts disposed in spaced relation on the shell, circuit-forming conductors between the first and second contacts, a switch mounted for movement on the shell and interposed in said conductors for closing and opening the circuit between said contacts, and means including a conducting closure for the open end of the shell having electrical connection with the first contact, in combination with a resistance-coil disposed within the shell intermediate the closure and the second contact 125
3. In an instrument of the class described, a shell open at an end, first and second contacts disposed in spaced relation on the shell, circuit-forming conductors between the first and second contacts, a switch mounted for movement on the shell and interposed in said conductors for closing and opening the circuit between said contacts, and means including a conducting closure for the open end of the shell having electrical connection with the first contact, in combination with a resistance-coil disposed within the shell intermediate the closure and the second contact 130

and having contacting electrical relation therewith, the coil being adapted for electrical connection with a source of current supply.

- 5 2. In an instrument of the class described, a shell open at an end, first and second contacts disposed in spaced relation on the shell, circuit-forming conductors between the first and second contacts, a switch mounted for movement on the shell and interposed in said 10 conductors for closing and opening the circuit between said contacts, an apertured conducting closure for the open end of the shell, and conducting means upon the shell for electrically connecting the closure with the first 15 contact, in combination with a resistance-coil disposed within the shell intermediate the closure and the second contact and having contacting electrical relation therewith, and 20 a socket-terminal upon the coil projecting outwardly of the shell through the aperture of the closure, whereby the coil is adapted for electrical connection with a source of supply.

- 25 3. In an instrument of the class described, a shell open at an end, first and second con-

tacts disposed in spaced relation on the shell, circuit-forming conductors between the first and second contacts, a switch mounted for movement on the shell and interposed in said 30 conductors for closing and opening the circuit between said contacts, an apertured conducting closure for the open end of the shell, and conducting means upon the shell for electrically connecting the closure with the first 35 contact, in combination with a spool disposed within the shell intermediate the closure and second contact, resistance wire coiled in units upon the spool, conducting-pieces on the spool for electrical connection with said wire 40 and having contacting electrical relation with the closure and second contact, a socket-terminal upon the spool projecting outwardly of the shell through the aperture of the closure whereby the resistance wire is adapted 45 for electrical connection with a source of supply, and means for selectively including units of said resistance wire within the circuit.

In testimony whereof, I have signed my 50 name to this specification.

ANTON HUMMEL.
